[57] CLAIM

The ornamental design for a personal computer enclosure, as shown and described.

DESCRIPTION

FIG. 1 is a left, top, front perspective view of the personal computer enclosure showing our new design;

FIG. 2 is a left side elevational view thereof;

FIG. 3 is a rear elevational view thereof;

FIG. 4 is a right side elevational view thereof;

FIG. 5 is a right, top, front perspective view thereof;

FIG. 6 is a front elevational view thereof; and,

FIG. 7 is a top plan view thereof.

FIGS. 2-4 and 6 are drawn on an enlarged scale.

FIG. 1

FIG. 4

FIG. 6

FIG. 5

FIG. 7
